UNITED STATES PATENT OFFICE

2,564,895

DEVICE FOR FOLDING TAPE FOR BRAIDING

Roger C. Griswold, Kingston, Mass.

Application May 7, 1949, Serial No. 91,925

3 Claims. (Cl. 93—84)

1

My invention is directed to improvements in a device for folding tape or strip material for braiding. My invention relates more particularly to hand tools which are adapted to receive tape or strips of fabric whereby the tape or strip is folded as it is drawn through the tube.

It is an object of my invention to provide a folding tool having a guide bar adjacent the large end into which the strip material is fed and to provide means for adjusting the guide bar to take care of different thicknesses of fabric.

Further objects and advantages of my improvements will be more readily apparent from the following description of a preferred embodiment thereof as illustrated in the accompanying drawings; in which

Figure 1 is a plan view of the folder and a strip being folded;

Figure 2 is a side elevation thereof;

Figure 3 is a vertical section taken on the plane indicated 3—3 in Figure 1;

Figure 4 is an enlarged vertical section taken on the plane indicated 4—4 in Figure 1; and

Figure 5 is an end view of the folder.

My invention is directed to improvements in the tool or strip folder which is used for folding strips of cloth just prior to braiding of the strips to make a braid commonly used in making braided rugs. The fabric strip 10 may be of various widths and thicknesses and is drawn through the folder 12 to make the folded strip 14. The folder 12 is preferably made of metal having smooth finished surfaces, although it might be shaped from plastic. If made of metal, it can be stamped out from flat metal sheets and then formed to the desired shape.

As shown, the folder 12 is formed into a cone. The large open end 16 receives the strip of fabric and the folded fabric is pulled out from the small open end 18. The side edges 20 of the folder 12 are curved inwardly, as shown in Fig. 3, extending adjacent the center of the folder near the small end, although, as shown in Fig. 4, the edge 22 will be at an angle with respect to the center line of the folder. This shape results in turning the raw edges of the fabric strip inwardly.

It is desirable, in a folder of this kind, to provide a guide for holding the fabric strip in place as it enters the folder. I provide a guide bar 24 which is separate from the folder 12. The guide bar 24 has the curved portions 26 which rest in the slots 28. A plurality of such slots are provided on each side of the folder so that the guide bar may be adjusted for different thicknesses of the fabric strip. The ends 30 of the guide bar 24

2

are turned upwardly, as shown in Fig. 5, and an elastic band 30 extends between the ends 30 and around the folder 12 to hold the guide bar in place.

5 In use, it is customary to provide three fabric strips and to have a folder on each strip. The folded strips are braided and from time to time the folders are pulled along the strips to make the folds. It will be apparent that by moving the guide bar nearer the small end 18 of the folder that the guide bar will be closer to the inner wall of the folder and thereby take care of thinner fabric strips.

I claim:

1. In a hand tool for folding fabric strip material used to make braid for rugs or similar articles comprising a substantially conical member having a large opening at one end into which the strip material is fed and a small opening at the other end from which the folded strip is pulled, said member having means within the member and adjacent the small end for turning the edges of the fabric strip inwardly as it is folded and a curved guide bar adjacent the large end of the member inwardly spaced from the inner wall thereof to define an arcuate opening through which the strip of material is fed, said guide bar being separate from said member and resilient means engaging said conical member and the ends of said guide bar for holding said guide bar in fixed spaced relationship with respect to said conical member for feeding strip material and means for adjusting said guide bar in position longitudinally of said conical member for a different thickness of material.

2. In a hand tool for folding fabric strip material used to make braid for rugs or similar articles comprising a substantially conical member having a large opening at one end into which the strip material is fed and a small opening at the other end from which the folded strip is pulled, said member having means within the member and adjacent the small end for turning the edges of the fabric strip inwardly as it is folded and a curved guide bar adjacent the large end of the member inwardly spaced from the inner wall thereof to define an arcuate opening through which the strip of material is fed, said member having a plurality of slots adjacent the large end, said guide bar adapted to be received in a pair of slots on opposite sides of the member and resilient means for adjustably fixing said guide bar in position.

3. In a hand tool for folding fabric strip material used to make braid for rugs or similar ar-

articles comprising a substantially conical member having a large opening at one end into which the strip material is fed and a small opening at the other end from which the folded strip is pulled, said member having means within the member and adjacent the small end for turning the edges of the fabric strip inwardly as it is folded and a curved guide bar adjacent the large end of the member inwardly spaced from the inner wall thereof to define an arcuate opening through which the strip of material is fed, and elastic means for adjustably holding said guided bar in fixed relation with respect to said member.
